UNITED STATES PATENT OFFICE.

HOWARD R. KEENEY, OF MELROSE, MASSACHUSETTS, ASSIGNOR TO HEYWOOD BROTHERS & WAKEFIELD COMPANY, OF WAKEFIELD, MASSACHUSETTS, A CORPORATION OF NEW JERSEY.

DESIGN FOR A CHILD'S VEHICLE.

55,054.

Specification for Design.

Patented May 4, 1920.

Application filed October 8, 1919. Serial No. 329,366. Term of patent 14 years.

To all whom it may concern:

Be it known that I, HOWARD R. KEENEY, a citizen of the United States, residing at Melrose, in the county of Middlesex and State of Massachusetts, have invented a new, original, and ornamental Design for a Child's Vehicle, of which the following is a specification, reference being had to the accompanying drawing, forming a part thereof.

The figure is a perspective view of a child's vehicle, showing my new design.

I claim:

The ornamental design for a child's vehicle, as shown.

In testimony whereof I have affixed my signature.

HOWARD R. KEENEY.
